UNITED STATES PATENT OFFICE.

HARVEY L. BRYANT, OF ROSELLE, NEW JERSEY, ASSIGNOR TO AMERICAN CAN COMPANY, OF NEW YORK, N. Y., A CORPORATION OF NEW JERSEY.

AUTOMATIC DIE FLANGER.

Application filed August 25, 1925. Serial No. 52,417.

My invention relates to flanging machines, and particularly to an improvement in such machines adapted to produce better results in the flanging of oblong, or other non-circular can bodies, than has been possible with the machines used for this purpose in the past. The flanging machines commonly used include oppositely disposed co-acting dies members, or flanging pads as they are termed in the art, which have a reciprocating movement, causing the same to move into and out of the ends of the can bodies, curling or bending the edges thereof outwardly to provide a suitable flange adapted to enter into the double seam joint by which the ends are attached. A flange formed in this manner on circular can bodies is entirely satisfactory, since, by reason of the circular shape of the body, the strains and stresses in the metal are substantially equal on all lines of cross section as the flange is being formed. In the case, however, of oblong or rectangular bodies, which usually are made with slightly rounded corners, the resistance offered by the straight sides and by said corners varies considerably, the resistance at the corners being sufficiently greater to cause an unevenness in the flange, which obviously interferes with efficient attachment of the ends. The mechanism used for round bodies is, therefore, not satisfactory for this type of bodies and it has been customary to provide squeezer jaws adapted to cooperate with the flanging pads in the flanging operation, said jaws being arranged to firmly back up or confine the exterior of the body at the ends thereof where the flanging action is taking place. Even with this mechanism, however, satisfactory results are not always obtained, due to the fact that the metal throughout the periphery of the body edge is closely and uniformly confined by the squeezer jaws and inasmuch as the metal at the rounded corners must be spread or stretched more than that along the sides of a rectangular body, a puckering, or unevenness, may be caused at said corners, thus producing an irregular flange. For an illustration of the type of mechanism just described, reference is made to Leffler Patent No. 905,719, and for an illustration of mechanism adapted to the flanging of circular bodies, reference may be had to Rudolphi Patent No. 1,055,418.

It is the object of my invention to provide

a flanging machine adapted to operate upon oblong or other non-circular can bodies of the type above mentioned in such manner as to avoid the unsatisfactory results referred to and to produce flanges which will be uniform throughout the periphery of the can body edges. This object is accomplished by providing mechanism adapted to confine the straight sides of a non-circular body during the flanging operation, but leaving the rounded corners without a support so that in the spreading or forming of the rounded corners, sufficient metal may be drawn from the straight sides to produce a uniform flange, the strains being thus equalized and the increased resistance at the corners being compensated for. I have found that in this manner I am able to obtain a flange free from wrinkles, or creases, and more perfect in all respects than the flanges produced by the mechanism heretofore in use.

A further and incidental advantage of the invention is that it dispenses with the exact machine work needed in making the squeezer jaw, or die type of mechanism, wherein the jaws must exactly fit each other without any variation.

Another feature of the machine of the invention is that the number of moving parts is reduced and maximum production obtained with a minimum amount of mechanical operation.

Numerous other objects and advantages of the invention will be apparent as it is better understood from the following description, which, taken in connection with the accompanying drawings, discloses a preferred embodiment thereof.

Referring to the drawings,

Figure 1 is a perspective view of an automatic can body flanging machine in which the principles of my invention are embodied;

Fig. 2 is a plan and sectional view, taken just above the supporting table;

Fig. 3 is a cross-sectional view, taken substantially on the section line 3—3 in Fig. 4;

Fig. 4 is a section taken substantially on the section line 4—4 in Fig. 2; and

Fig. 5 is a central sectional view, taken substantially on the line 5—5 in Fig. 4.

On said drawings, I have shown, for illustrative purposes only, a machine in which the operating parts are supported upon a frame comprising a bed 11, legs 12 and angle 110

iron connecting members, or braces, 13. Said operating parts comprise primarily two side walls 14 supported by brackets 15 adjustably mounted upon a fixed part 16 supported 5 upon the table 11 and held in place by means of screws 17, and two die members, or flanging pads, 18 which are secured to slides 19 mounted in guideways 21 and adapted to be reciprocated in timed relationship to the 10 feeding of the can bodies, in a manner which will be presently described. Said pads are formed with tapered surfaces 22, adapted to enter the mouth of the can and with channels 23 at the base of said tapered surfaces 15 adapted to receive and shape the flange as said pads move toward each other and into opposite ends of said can body. The outer wall 24 of said channel provides a limiting stop for the flange and the members 14, together with other parts to be later described, 20 hold the body in position to cause said flange to be directed into said channel upon inward movement of said pads. Said side walls 14 are tapered at the top, as indicated at 25, to facilitate the entrance of the can bodies therebetween and are adjusted in accordance with the size of said bodies to provide a guideway through which said bodies move in close relationship to said walls, 30 whereby the walls provide a positive support for the sides of said can bodies. Hinge blocks 26 are pivoted at 27 in supports 28 at the top and bottom of said flanging pads 18 and serve to support the short, straight 35 sides of the can body during the flanging operation. It will be evident that said blocks may move readily over the end of the can upon axial movement of said flanging pads toward each other before the flanges are projected and they are held in contact with the can wall by means of flat springs 29, secured by screws 31 to top parts 32 on said flanging pads 18.

The cans are fed into the machine through 45 a runway 33 and are supported during the flanging operation by a vertical conveyer, comprising a chain 34 carrying lugs or supports 35 and moving about sprockets 36 and 37 mounted, respectively, upon shafts 38 and 50 39, which have bearings 41 and 42 in opposite ends of brackets 43 secured by means of screws 44 to the table 11. Intermittent movement is imparted to said conveyer by means of a pawl and ratchet mechanism, indicated at 45, at one end of the shaft 38 and operated by a rod 46 extending from a yoke 47, which carries a cam following roller 48 riding in a cam groove in a cam 49, mounted upon a shaft 51 journaled in bearings 52 extended from the table 11. Said shaft is adapted to be driven from any suitable source of power by means of a pulley 53, mounted at one end thereof and carries at its opposite end a crank 54, the crank pin 55 of 55 which is connected by means of a link 56

with a slide 57 mounted in a guideway 58 in said table 11. Said slide 57 is connected by rods 59 with levers 61, pivoted at 62 to the frame, said levers being connected by links 63 with sliding members 64 carrying the slides 19 to which the flanging pads 18 are secured. For the sake of rigidity, the pivot points 62 are connected by tie rods 65 and it will be evident that the flanging pads 18 are moved toward and from each other 75 periodically by the mechanism just described. This reciprocating movement is in timed relationship to the feeding of the cans, the latter being held in stationary position as said pads move inwardly and until 80 they have moved away sufficiently to cause the pivoted blocks 26 to snap over the formed flange, which I have indicated by the reference character 66, the can body being designated by the character 67. Said bodies 85 67 are supported upon the lugs 35 of the conveyer 34, as they are transferred through the flanging mechanism, and are discharged through a discharge chute 68 after the flanging operation has been completed. Said conveyer operates in timed relationship with respect to the movement of the flanging pads, as hereinbefore stated. The shaft 39, upon which said sprocket 37 is mounted, is idle and said sprocket is so arranged as to cause 90 said conveyer lugs 35 to support the cans as they are moved downwardly underneath the table of the machine and deposited in the discharge chute, or runway, 68 through which they move by gravity or are fed in 95 any preferred manner.

It will be apparent, from viewing Fig. 5 particularly of the drawings, that the rounded corners 69 of the cans are unsupported, being arranged between the side walls 14 and the pivoted blocks 26 and being free to permit unrestrained flow of the metal thereto from the straight, supported side walls during the flanging action.

From the foregoing, it is believed that the 100 operation of the machine will be apparent. The unflanged can bodies 67 are fed down through the chute 33 and are engaged by the lugs 35 of the conveyer chain 34 when said chain is at rest. Upon movement of the chain, the can body is lowered thereby and is brought to rest in axial alignment with the flanging pads 18, which move inwardly and form outwardly extending flanges upon the opposite ends of the body, as previously described. The flanging pads are then separated, at which time the spring-held blocks 26 snap over and off of the formed flanges 66. This takes place 115 while the can body is at rest, the conveyer chain then moving to lower the can body from the flanging position and bringing in the next can body to said flanging position. The flanged body is moved downwardly by a series of step movements and is finally 120 125 130

projected from the conveyer chain 34 into the discharge chute 68.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

I claim:

1. In a can body flanging machine, the combination of means for supporting non-circular can bodies with rounded corners at a flanging station, a flanging die movable axially of a supported can body and having a tapered head adapted to enter an open end of said body, said die having a formation adapted to produce an outwardly extending flange upon said body, and means for supporting the median parts of the side walls of said can body, said supporting means terminating so as not to extend to the corners of the can body and so as to leave the rounded corners thereof unsupported, whereby the strains upon the flange along said straight sides and at the corners are equalized and sufficient metal may enter the flange at the corners from said sides to produce a substantially uniform flange throughout the periphery of the body edge.

2. In a can body flanging machine, the combination of means for supporting non-circular can bodies with rounded corners at a flanging station, means adapted to enter the mouth of a can body to form an edge flange on the latter, and means for supporting the median parts of substantially straight portions of said body on the exterior thereof, and at places between the corners thereof, said supporting means terminating so as not to extend to the corners of the can body, whereby the said straight portions of the body are unsupported at said corners during the flanging operations.

3. In a body flanging machine, the combination of means for supporting non-circular can bodies having rounded corners at a flanging station, means adapted to enter the mouth of a can body to form an edge flange on the latter, and means for supporting the median parts of straight portions of said body on the exterior thereof, said supporting means terminating so as not to extend to the corners of the can body, whereby the said straight portions of the body are unsupported at said corners during the flanging operations, said supporting means including pivoted members yieldably held in contact

with the body and adapted to move outwardly over the flange of the body to permit removal of the latter after flanging.

4. In a body flanging machine, the combination of means for supporting non-circular can bodies having rounded corners at a flanging station, means adapted to enter the mouth of a can body to form an edge flange on the latter, and means for supporting the median parts of straight portions of said body on the exterior thereof, said supporting means terminating so as not to extend to the corners of the can body, whereby the said straight portions of the body are unsupported at said corners during the flanging operations, said supporting means including pivoted members yieldably held in contact with the body and adapted to move outwardly over the flange of the body to permit removal of the latter after flanging, said members being movable with said flanging means.

5. In a can body flanging machine, the combination of means for supporting non-circular can bodies at a flanging station, said bodies having substantially straight wall portions and curved wall portions, means for flanging said can bodies uniformly throughout the periphery of the wall thereof, and means for backing up the substantially straight wall portions during the flanging operation, said backing up means having spaces between them opposite to the curved wall portions.

6. In a can body flanging machine, the combination of a supporting frame providing a flanging station, means for delivering non-circular can bodies to said station, spaced apart side guides at said station between which said bodies are directed and by which they are exteriorly supported, and reciprocating means for flanging an open end of said body, said body having substantially straight wall portions and curved wall portions and the curved portions being at the spaces between said side guides and unsupported by said guides.

7. In a can body flanging machine, the combination of means for supporting non-circular can bodies having rounded corners at a flanging station, reciprocating means movable in opposite directions and adapted to enter opposite ends of the can body to flange the same, and spaced apart guides for supporting substantially straight portions of said body on the exterior thereof, the rounded corners of the body being located at the spaces between said guides and unsupported during the flanging operations.

HARVEY L. BRYANT.
